TIGHT-LOCK CAR COUPLER

Herbert E. Van Dorn, Chicago, Ill., assignor to
 The Dornvan Corporation, a corporation of Illinois

Application August 19, 1937, Serial No. 159,829

7 Claims. (Cl. 213—76)

In my prior Patent No 1,403,657, there is illustrated a car coupler of the tight-lock type having a locking dog in the form of a horizontally-swinging bail which engages with and embraces a nose projecting forwardly from a cooperating, similar coupler in making a coupling. The present invention relates to couplers of the character illustrated in said patent and has for its object to improve the same.

10 In my prior coupler the outer, vertical working face of the coupler nose, which is engaged by the vertical member of the locking dog, is so shaped that a wedging action takes place between the nose of one coupler and the locking dog in a companion coupler, in the act of coupling; thereby causing the nose to be wedged tightly in place in the cooperating coupler. This configuration of the coupler nose provides compensation for wear in that, as wear occurs, the locking dog need only swing farther forward upon the nose. The angle through which the locking dog may swing from a working position when the parts are new to a final working position in an old coupler is small. Therefore, if it be desired to compensate for a very considerable wear on the working face of the locking dog, the slope of the cooperating facing on the coupler nose must be made relatively steep. In accordance with my invention I so shape the working face on the nose and the complementary face on the locking dog that the face on the locking dog always lies at a very small angle, say about 2°, to a plane tangent to the nose along the line of contact between the dog and the nose. Therefore, viewed in one of its aspects, the present invention may be said to have for its object to make provision for compensating for any desired amount of wear on the locking dog, without making the angle of the wedge, as it were, large enough to reduce the effectiveness of the grip of the locking dog on the nose under all conditions. In other words, the invention may be said to have for its object to improve the aforesaid prior coupler so as to take care of a much greater amount of wear without diminishing the effectiveness of the hold of the locking dog on the nose of the coupler.

A further object of the present invention is so to connect a manual operating lever to the locking dog that the lever may remain stationary while the dog is swinging into a locking position in the act of uncoupling and also, while the dog is being pushed back by the nose of an oncoming coupler and then returns to a locking position, 55 in effecting a coupling.

The various features of novelty whereby my invention is characterized will hereinafter be pointed out with particularity in the claims; but, for a full understanding of my invention and of its objects and advantages, reference may be had 5 to the following detailed description taken in connection with the accompanying drawings, wherein:

Figure 1 is a side elevation of a coupler head embodying the present invention; Fig. 2 is a vertical longitudinal section, on a larger scale than Fig. 1, through the coupler head, all of the movable parts within the head being shown in elevation; Fig. 3 is a horizontal section through the head, all of the movable parts within the head 15 except the pivotal shaft of the locking dog, being shown in plan; Fig. 4 is a view looking forwardly from behind the coupler head, the shell or casing of the head being shown as a section taken on line 4—4 of Fig. 3; Fig. 5 is a section 20 taken approximately on line 5—5 of Fig. 3; Fig. 6 is a section on line 6—6 of Fig. 2, showing only a small fragment of the mechanism; Fig. 7 is a section on line 7—7 of Fig. 2, illustrating still another fragment; and Figs. 8, 9 and 10 are more 25 or less diagrammatic views illustrating the manner in which takeup for wear is accomplished.

Referring to the drawings, 1 represents a hollow coupler head having at one side a forwardly projecting nose 2 and being open at the front 30 beside this nose to permit the entrance of the nose of a companion coupler. Within the coupler head is a locking dog 3 in the form of a yoke or bail that swings about a vertical axis through the free ends of the arms of the yoke which lie 35 one above the other; the nose of a companion coupler being adapted to be embraced and tightly gripped by this yoke. A vertical hinge pin 4 for the locking dog or yoke is journalled at its ends in a pair of cylindrical bearing blocks 5, 5 rotatable in suitable bearings in the top and bottom walls of the coupler head; the axis of the hinge pin being eccentric to the common axis of the bearing blocks 5, 5. Consequently, if the bearing blocks are turned, the hinge pin is shifted bodily. 40 On the pin 4, between the upper and lower arms of the yoke or bail of the locking dog, is a more or less cylindrical casting 6. Each of the bearing blocks 5, each of the two arms of the locking dog, and the casting 6 is provided with one or more 50 arms projecting rearwardly therefrom, radially of the hinge pin. The arms on the bearing blocks are indicated at 7, 7, those on the locking dog at 8, 8, and those on the casting 6 at 9, 9. Each of the arms 7 and 8 contains a deep notch 55

opening out through the rear edge thereof. The arms 9 have therein openings 10 that register with each other and with the notches in the arms 7 and 8. A pin 11 which is a fit in the openings 10, 10 extends vertically through these openings, and through the notches in the arms 7 and 8. The notches 12, in the arms 7 and 8, as best shown in Fig. 3, have a width substantially equal to the diameter of the pin 11, whereas the notches 14 in the arms 8 on the locking dog, have an angular width, as best shown in Fig. 6, considerably greater than the diameter of the pin 11. The pin 11 is fastened to one of the arms 9 by means of a small pin 15. The casting 6 has two additional arms 16, 16 projecting laterally behind the hollow nose 2. A compression spring 17 is arranged between an abutment 18 lying between the arms 16 and secured thereto for rocking movements by a pin 19, and an abutment 20 20 in the front end of the nose 2.

Whenever left free to do so, the spring 17 rocks the casting 6 in the clockwise direction, as viewed in Fig. 3. Since the pin 11 moves with the casting 6 and fills the width of the slots 14 in the 25 arms of the bearing blocks 5, these bearing blocks are also turned in the clockwise direction. If the pin 11 occupied the position, relatively to the notches 14 in the arms 8 of the locking yoke, as indicated in dotted lines in Fig. 6, the locking dog 30 is not caused to move until the pin 11 travels across the notch 14 into the full line position indicated in Fig. 6, whereupon the casting 6, the bearing blocks 5 and the locking dog are caused to move in unison with each other. In Fig. 3 the 35 locking dog is shown in what may be regarded as its locking position before wear has taken place. The nose of a companion coupler, shown in dotted lines in Fig. 3, serves as a stop to prevent further swinging movement of the locking dog, and 40 therefore, of the other parts. However, were this coupler nose not present, the locking dog would swing in the clockwise direction through an additional angle of perhaps 16°.

It will be seen that the bearing blocks 5 are 45 so positioned that as these blocks turn in the clockwise direction toward and past the position illustrated in Fig. 5, the hinge pin 4 is moved laterally farther behind the nose forming part of the same coupler head. In other words, the 50 locking yoke or dog is moved bodily in a radial direction to draw it tightly against the nose of a cooperating coupler. On the other hand, whenever the locking dog is swung in the counter-clockwise direction, as viewed in Fig. 3, either 55 through engagement with the nose of an oncoming coupler, or through actuating means acting on the pin 11, the locking yoke or dog is shifted radially in the opposite direction. It will be seen, however, that a swinging movement of the locking dog or yoke is always accomplished by a slight lengthwise shifting of the same. The lost motion between the pin 11 and the locking dog or yoke has for its purpose to relieve the pressure between the working face 21 on the dog and the 60 cooperating working face 22 on the nose of a companion coupler, in the act of uncoupling, before the yoke begins to swing back into a release position; this being a function that is also performed by the eccentric in my aforesaid prior 65 patent. The only purpose of the eccentrics in my prior patent is to relieve the pressure, whereas in the present instance the eccentrics serve as a takeup during the entire range of forward swinging movements of the locking dog.

70 The locking dog may conveniently be shifted

into its unlocking position by a horizontally swinging hand lever 24 hingedly connected at its front end, as at 25, to the side of the coupler head. A torsion spring 26 serves constantly to hold the lever close to the head. The connection 5 between the lever and the locking dog is a connecting rod 27 having at its outer end an elongated slot 28 through which passes a pin 29 fixed to the lever 24. The connecting rod extends through a hole 30 in the side wall of the coupler head and has at its inner end a long slot 31 through which the pin 11 passes. When two couplers are engaged, the parts occupy the position shown in Fig. 3; the pins 29 and 11 being at corresponding ends of their slots 28 and 31. In order to bring 10 the locking dog into its release position, the lever 24 need only be swung in the counter-clockwise direction, as viewed in Fig. 3, until the pin 29 reaches the outer end of the slot 28, whereupon 15 the connecting rod will begin to pull on the pin 11 20 so as to turn the casting 6 in the counterclockwise direction. The relation between the pin 11 and the notches 14 in the arms 8 on the locking dog is at this time that indicated in full lines in Fig. 6. Consequently, the casting 6 and the eccentric 25 bearing blocks are turned through a small angle, without any turning movement of the locking yoke occurring, until the pin 11 crosses the notches 14 and assumes the position illustrated in dotted lines in Fig. 6. During this preliminary 30 turning movement of the eccentrics, a simple radial movement of the locking dog occurs in the direction to separate the working faces 21 and 22, so that there is no frictional resistance between these working faces to interfere with the 35 free rearwardly swinging movement of the dog into its release position.

When the locking dog is swung back as far as it will go through the operation of the hand lever, it is locked in its farthest back or release position 40 by any usual or suitable catch devices.

In the arrangement shown there is a link 32 connecting the pin 11 with a horizontally-swinging arm 34 in the rear portion of the coupler. Cooperating with this arm is a horizontally 45 swinging spring pressed pawl 35 to hold the locking dog in its release position; the pawl being adapted to be tripped by the nose of the companion coupler when the same is withdrawn upon the separation of the cars from each other. This 50 construction is the same as that illustrated in my prior Patent No. 1,475,609, except that the arm 34 is not fixed to the shaft of the operating lever and does not serve any other purpose than to assist in holding the dog in its release position. 55

When the lever 24 is swung outwardly from the side of the coupler, causing the locking dog to swing back into its release position and the spring 17 to be compressed, the dog engages the pawl 35 in the usual way and swings the end 36 thereof rearwardly beside the face 37 on the arm 34; thereby causing the pawl to hold the dog in release position until the pawl is tripped. When the operator lets go of the lever 24, the spring 26 returns the lever to its normal position of rest, as 60 shown in Fig. 3; the slot 31 being long enough to permit the connecting rod to return to the position which it occupies in Fig. 3, while the locking dog remains stationary. Then, when the cars 65 separate and the coupler nose shown in dotted lines in Fig. 3 moves out through the front end of the coupler, it trips the pawl and allows the spring 17 to throw the locking dog forward again. This forward movement of the dog is accomplished without producing any movement of the 70 75

lever 24, the pin 11 simply travelling along the slot 31 in the connecting rod. Fig. 3 shows the locking dog in a normal coupling position; but, when the dog swings forwards upon separation of the couplers, it moves forward beyond that position. Consequently, the pin 11 may at this time pull the connecting rod 27 inwardly, such movement being permitted by the pin and slot connection between the connecting rod and the hand lever. When cars come together to effect an automatic coupling, the nose of each coupler enters the opposite coupler, pushes back the locking dog which it encounters and then permits the dog to swing forward into locking relation thereto. These latter movements of the dogs take place without disturbing the respective hand levers on the couplers. It will thus be seen that there is no movement of the hand lever of a coupler except at the time of setting the locking dog in its release position.

In Figs. 8 to 10 I have illustrated, more or less diagrammatically, the manner in which a locking dog and the nose of a coupler cooperate in effecting a tight lock and in taking up wear. The diagrams are based on locking positions covering a range of about sixteen degrees. In Fig. 8 the locking dog is shown in full lines in the normal locking position, before wear occurs, with respect to the nose of another coupler; whereas, in dotted lines it is shown as having been shifted radially by reason of the turning of the eccentrics through an angle of sixteen degrees. In Fig. 9 the extent to which the working or locking face of the locking dog is shifted inwardly with respect to the coupler nose in swinging through its range of locking positions is shown; no account being taken of the effect of the eccentrics. In Fig. 10 is shown the result of the combined actions illustrated in Figs. 8 and 9; Fig. 10 showing the operation of the locking dog in actual practice. It will be seen that one-half of the total takeup may be provided by the action of the eccentrics and the other half by the configuration of the cooperating locking faces. Thus, if a takeup of three-sixteenths of an inch is desired, the eccentrics may provide three thirty-seconds of that amount and the contours the remaining three thirty-seconds.

The simplest way of properly shaping the locking surface on the coupler nose is to machine it as a section of a cylinder having its axis parallel to the axis of the hinge of the dog in a cooperating coupler, but spaced somewhat nearer the front of the latter coupler (when the two couplers are in coupled relation) than is the said hinge pin axis. The axis of the hinge pin of the locking dog is in advance of the axis of the corresponding eccentrics which is the effective hinge axis of the dog while in a locking position. In Figs. 8 to 10, A and B represent respectively the axis of the eccentrics and of the corresponding hinge pin in a coupler, while C represents the axis of the locking face on the coupler nose with which the locking dog engages.

In Fig. 9 the line D represents a tangent to the face 22 at the end of the radius C, while the line E is a continuation of the line of the face 21 of the locking dog. These two lines lie at an angle of about two degrees with respect to each other. As the working face of the dog wears away, the dog swings farther forward but its working face always lies at the same angle to the new portion of the cooperating face of the nose. Since the angle between the two surfaces that are being wedged together while cars remain coupled is

very small, the greater the pressure, the more positive will be the locking action; and since this same small angle is maintained after wear takes place, the coupler will lock itself securely to a companion coupler until the locking dog becomes so worn that it can swing no farther forward.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In combination, a car coupler head, a dog in the head to engage with a part on a second head to lock the two heads together, and a mounting for said dog to permit it to be brought into wedging engagement with the said part of the second coupler through simultaneous swinging and bodily radial movement and to be shifted radially away from said part before beginning a swinging movement in unlocking.

2. In combination, a car coupler head, a dog in the head to engage with a part on a second head to lock the two heads together, a hinge pin whose axis at all times forms the hinge axis for the dog, an actuator for said dog, a driving connection permitting a lost motion between the actuator and the dog, and means operated by the actuator to shift the hinge pin transversely of its axis when the actuator is moved.

3. In combination, a coupler head, a dog in the head to engage with a part on a second head to lock the two heads together, a mounting for said dog comprising separated bearing blocks rotatable about a common fixed axis and a hinge pin supported by the said blocks with its axis spaced apart from and parallel to the aforesaid axis, an actuator for turning said blocks, and a driving connection containing a lost motion between said actuator and said dog.

4. In combination, a hollow car coupler head, a dog in the head to engage with a member on a second similar head that enters the first head in coupling to lock the two heads together, and a mounting for said dog to permit it to be brought into wedging engagement with a working face of the said member of the second coupler through simultaneous swinging and bodily radial movement and to be shifted radially away from said working face before beginning a swinging movement in unlocking; the said working face curving gradually outwardly from the path of travel of the cooperating face on the dog from the zone of contact between such faces before wear takes place, thereby insuring a tight lock when the lock swings farther forward, in locking, after wear occurs.

5. In combination, a car coupler head, a dog in the head to engage with a part on a second head to lock the two heads together, a hinge pin whose axis at all times forms the hinge axis for the dog, a spring-pressed actuator for said dog, a driving connection permitting a lost motion between the actuator and the dog, means operated by the actuator to shift the hinge pin transversely of its axis when the actuator is moved, a lever pivoted at one end to the side of the coupler head, a spring tending constantly to hold the lever lying against the head, and a connection between the lever and the actuator having therein a lost motion permitting the dog to move from a locking position into a release position without moving the lever.

6. In combination, a car coupler head, a dog in the head to engage with a part on a second head to lock the two heads together, a hinge pin whose axis at all times forms the hinge axis for the dog, a spring-pressed actuator for said dog, a driving connection permitting a lost motion between the actuator and the dog, means operated by the actuator to shift the hinge pin transversely of its axis when the actuator is moved, a lever pivoted at one end to the side of the coupler head, a spring tending constantly to hold the lever flat against the head, and a connecting means between the lever and the actuator having therein a lost motion permitting the

dog to move from a locking position into a release position or from a release position to a locking position without causing the lever to move.

7. In combination, a car coupler head, a dog in the head to engage with a part on a second head to lock the two heads together, rotatable, axially aligned bearing members mounted in said head on opposite sides of the dog, and a hinge pin for the dog supported by said bearing members with its axis parallel to and spaced apart from the axis of rotation of said bearing members.

HERBERT E. VAN DORN.
